US00D535903S

(12) **United States Design Patent** (10) Patent No.: **US D535,903 S**
(45) Date of Patent: **** Jan. 30, 2007**

(54) **DETECTOR**

(75) Inventor: **Pierre Nicolai**, Clavier (BE)

(73) Assignee: **Bureau d'Electronique Appliquee, S.A.**, Angleur (BE)

(**) Term: **14 Years**

(21) Appl. No.: **29/233,921**

(22) Filed: **Jul. 11, 2005**

(30) **Foreign Application Priority Data**

Jan. 11, 2005 (EM) 000277421

(51) **LOC (8) Cl.** **10-05**

(52) **U.S. Cl.** **D10/106**

(58) **Field of Classification Search** D25/38, D25/164, 122; D23/267, 259; D10/78, 65, D10/47, 116, 106, 103, 121, 39, 104; D12/204, D12/213; D27/192; 73/61.43, 49.2; 340/605; D14/225, 218, 371; D13/168

See application file for complete search history.
